CLAIM

The ornamental design for a knee wrap, as shown and described.

DESCRIPTION

FIG. 1 is a perspective view of a knee wrap in accordance with the design;

FIG. 2 is a perspective view of the knee wrap of FIG. 1 in use; FIG. 3 is a perspective view of the knee wrap of FIG. 1 in use; and,

FIG. 4 is a top plan view of the knee wrap in accordance with the design.

The broken line showing of parts of the drawings is included for the purpose of illustrating use and environment and forms no part of the claimed design.
